UNITED STATES PATENT OFFICE

105,377

DESIGN FOR A DRESS

Seymour H. Gross, New York, N. Y.

Application May 10, 1937, Serial No. 69,255

Term of patent 3½ years

To whom it may concern:

Be it known that I, Seymour H. Gross, a citizen of the United States, residing at New York, in the city, county, and State of New York, have invented a new, original, and ornamental Design for a Dress, of which the following is a specification, reference being had to the accompanying drawing, forming part thereof, wherein—

Fig. 2 is a back view of the dress showing my new design.

The characteristic feature of my design resides in the combination on the dress as shown of the illustrated arrangement of ornamentations on the sleeves and on the central panel.

I claim:

The ornamental design for a dress substantially as shown and described.

SEYMOUR H. GROSS.
